UNITED STATES PATENT OFFICE.

LEO A. McDONAGH, OF LINDEN, NEW JERSEY.

DESIGN FOR A BADGE.

47,247.

Specification for Design.

Patented Apr. 20, 1915.

Application filed January 9, 1915. Serial No. 1,469. Term of patent 3½ years.

To all whom it may concern:

Be it known that I, LEO A. McDONAGH, a citizen of the United States, residing at Linden, in the county of Union and State of New Jersey, have invented a new, original, and ornamental Design for a Badge, of which the following is a specification, reference being had to the accompanying drawing, forming part thereof.

The figure is an elevation of a badge, showing my new design.

I claim:

The ornamental design for a badge, as shown.

LEO A. McDONAGH.

Witnesses:

JOHN W. McDONAGH,
B. JOFFE.
